UNITED STATES PATENT OFFICE.

BERNARD RICH, OF ST. LOUIS, MISSOURI, ASSIGNOR TO AMERICAN SYRUP & PRESERVING COMPANY, OF ST. LOUIS, MISSOURI, A CORPORATION OF TENNESSEE.

BOX-SEALING MACHINE.

Application filed December 1, 1924. Serial No. 753,078.

To all whom it may concern:

Be it known that I, BERNARD RICH, a citizen of the United States of America, a resident of the city of St. Louis, in the State of Missouri, have invented certain new and useful Improvements in Box-Sealing Machines, of which the following is a full, clear, and exact description, reference being had to the accompanying drawings, forming a part of this specification.

This invention relates generally to improvements in box-sealing machines, and particularly to a machine which is adapted to retain the flaps of cardboard boxes in a folded condition to permit the adhesive, which has been previously applied to said flaps, to dry and thus secure said flaps in closed positions.

Prior to this invention machines have been produced for sealing cardboard boxes, but most of these machines included traveling rollers which were caused to travel over the folded flaps of the boxes while the adhesive was drying. It has been found that for adhesive used to seal cardboard boxes to dry properly, said adhesive must be undisturbed during the drying operation. In using a machine of the type having traveling rollers, it was discovered that the passage of the rollers over the flaps while the adhesive was drying would disturb or agitate said adhesive to such extent that it would not dry properly, with the result that the box would not be properly sealed.

The main object of the present invention is to produce a machine having traveling members which will retain the flaps of the boxes in folded positions while the adhesive on said flaps is drying. However, instead of moving relative to the flaps as did the traveling rollers of the machines heretofore used, the traveling members of my improved machine are stationary with respect to the boxes, said boxes being caused to travel with said traveling members. By this arrangement the adhesive is not disturbed during the drying operation, and as a result the boxes are very securely sealed.

With the foregoing and other objects in view, the invention comprises the novel construction, combination and arrangement of parts hereinafter more specifically described and illustrated in the accompanying drawings, wherein is shown the preferred embodiment of the invention. However, it is

to be understood that the invention comprehends changes, variations and modifications which come within the scope of the claim hereunto appended.

Fig. I is a longitudinal section of a machine made in accordance with my invention.

Fig. II is a section on line II-II of Fig. I.

Fig. III is a fragmentary section showing the manner in which pressure members of my improved machine are supported.

Fig. IV is a horizontal section on line IV-IV of Fig. II.

Fig. V is a perspective of a box of the type which may be sealed by my machine.

In the drawings, A designates my improved sealing machine which comprises a lower stationary frame B provided with a plurality of legs C by which said lower frame is supported. The lower frame B is provided with a horizontal row of rollers 1 mounted on transverse rods 1', which rollers are intended for a purpose to be hereinafter set forth.

Arranged above the lower frame B is an upper frame D. The upper frame D comprises a pair of oppositely disposed rectangular side members 2 which support transverse shafts 3 and 4, on each of which is mounted a pair of spaced apart sprocket wheels, the sprocket wheels on the shaft 3 being designated by the reference character 5 and the sprocket wheels on the shaft 4 being designated by the reference character 6. Operating over the sprocket wheels 5 and 6 is a pair of sprocket chains 7. Arranged transversely of the pair of sprocket chains 7 is a plurality of presser members 8, said presser members being supported by and adapted to travel with said sprocket chains 7. It will be noted that the transverse presser members 8 are supported by certain of the links of the sprocket chains 7, and by referring to Fig. III of the drawing it will be seen that these links are each provided with an outwardly extending lug 9 having an aperture 10 formed therethrough. Located at the opposite ends of each of the transverse presser members is a pair of pins 11 which are extended through the apertures 10 in the associated lugs 9, as shown clearly in Fig. III. 12 designates coil springs which are interposed between the presser members 8 and the associated lugs 9, said coil springs being adapted to force said presser members 110

in a direction away from said lugs. Located at the free ends of the pins 11 are nuts 13 which limit the movement of said presser members in a direction away from the lugs 9.

5 Arranged at an end of the shaft 3 is a comparatively large gear wheel 14 which meshes with a smaller gear wheel 15' fixed to a shaft 16'. Mounted on the shaft 16' is a pulley 17' to which rotary movement 10 is imparted by a belt 18'. It is apparent that the relative sizes of the gear wheels 14' and 15' will cause the shaft 3 to be rotated very slowly, which slow movement will be imparted to the sprocket chains 7 and presser 15 members 8.

The operation of my improved machine is as follows:

The goods which are to be packed in the boxes X are placed within one of said boxes, 20 after which the adhesive is located on the inside faces of the flaps X^a and on the outside faces of the flaps X^b of the box. The flaps are then folded so that the top of the box is closed and said box is placed on the rollers 1, which are located at the extreme left end 25 of the lower frame B. The box is then moved inwardly until it is in such position that one of the transverse presser members moving over the sprocket wheel 5 will contact with the folded flaps of the box and 30 will force said flaps into firm contact with each other. As the transverse presser members which are in contact with the box move along the lower flights of the sprocket 35 chains 7 in the direction indicated by the arrow in Fig. I, the box will be carried with said presser members, the rollers 1 over which the box passes reducing the friction of the passage of said box to a minimum.

40 It is therefore plain that the presser members 8 and the box X move the entire length of the machine without any relative movement between said presser members and said box, and it is apparent, in view of this fact, 45 that the adhesive would be permitted to dry without disturbance during the passage of the box through the machine.

By providing spring-pressed presser members it is plain that said presser members 50 are at all times forced into firm contact with the flaps of the boxes which are passing through the machine, and in addition to this it provides means whereby said presser members may yield in the event that they 55 encounter an obstruction, such as an improperly folded flap.

To permit of boxes of different heights being sealed by my improved machine, I provide means for adjusting the upper frame 60 D vertically with respect to the lower frame B. This will increase or diminish the distance between the presser members 8 traveling along the lower flights of the sprocket chains 7 and the top faces of the rollers 1.

To illustrate a simple means for effecting the 65 adjustment mentioned, I employ a plurality of upright members 15 which are secured to the lower frame B of the machine, said upright members being extended some distance above the rollers 1. The upper frame D is 70 also provided with a plurality of upright members 16 which are arranged adjacent to the upright members 15. Fixed to the lower ends of the upright members 16 are plates 17 provided with laterally extended portions 75 18, there being one of said plates at the lower end of each individual upright 16. Secured to each upright member 15 is a pair of vertically arranged bars 19 which are spaced apart from each other in a horizontal direction 80 to provide a trackway between said vertical bars. The upright members 15 and 16, as already stated, are arranged adjacent to each other, and the laterally extending portions 18 of the plates 17 are extended into the trackways between the vertical bars 19. It is apparent from this that the upright members 16 may move vertically with respect to the upright members 15, and it is also quite plain that because the portions 18 90 of the plates 17 extend between the vertical bars 19 said upright members 16 may not move laterally nor longitudinally of the machine with respect to the upright members 15. Formed on each of the upright 95 members 15 is a lug 20 having an internally threaded opening through which a threaded rod 21 passes. The upper ends of the threaded rods 21 are arranged to bear against the lower faces of the plates 17. It 100 is plain, in view of the construction just described, that by rotating the threaded rods 21 the entire upper frame D may be elevated or lowered, thus regulating the distance between the top faces of the rollers 1 and the 105 bottom faces of the lower row of presser members 8.

It will be noted that the presser members 8 are each provided with beveled side edges. These edges are provided to permit 110 the presser members to move in an arc of a circle about the sprocket wheels 5 and 6 without causing the edges of said presser members to be forced into the boxes.

I claim:

A box-sealing machine comprising a member provided with bottom rollers along which the boxes to be sealed travel, and spring-pressed presser members adapted to contact with the boxes, said presser members only being adapted to impart movement to the boxes to move them longitudinally of the first mentioned member, said rollers aiding in the free passage of said boxes along said member.

In testimony that I claim the foregoing I hereunto affix my signature.

BERNARD RICH.
